UNITED STATES PATENT OFFICE.

FRED S. OLIVER, OF SAN FRANCISCO, CALIFORNIA.

GRAVITY-VALVE.

1,161,243.

Specification of Letters Patent. Patented Nov. 23, 1915.

Application filed April 21, 1913. Serial No. 762,698.

To all whom it may concern:

Be it known that I, FRED S. OLIVER, a citizen of the Dominion of Canada, and a resident of the city and county of San Francisco, State of California, have invented certain new and useful Improvements in Gravity-Valves, of which the following is a specification.

The invention relates to valves for controlling the flow of fluids.

The object of the invention is to provide a valve for controlling the flow of fluids, which is operated by a variation in gravity of the fluid.

Another object of the invention is to provide means for allowing the discharge of fluid from a receptacle, when the fluid reaches a certain predetermined gravity.

The invention possesses other advantageous features, which, with the foregoing, will be set forth at length in the following description where I shall outline in full that form of the invention which I have selected for illustration in the drawings accompanying and forming part of the present specification. The novelty of the invention will be included in the claims succeeding said description. From this it will be apparent that I do not restrict myself to the showing made by said drawings and description, as I may adopt many variations within the scope of my invention as expressed in said claims.

Referring to said drawings: Figure 1 is an elevation, partly in section, of the valve of my invention. Fig. 2 is an elevation, partly in section, showing one of the applications of the valve of my invention.

The device is adapted to be used for separating fluids of different specific gravities, and is not limited in use to any particular fluid, nor is its application limited to any particular type of apparatus.

In the drawings I have shown the device as used in connection with a gasolene vaporizing or carbureting apparatus, but this is shown merely to illustrate the operation of the device.

The device comprises a receptacle 2 adapted to contain a fluid, and provided at its lower end with an outlet passage 3. Arranged in the receptacle is a closed hollow tube or body 4 provided on its lower end with a stem or needle 5 adapted to control the aperture or passage 3. The hollow tube or float is preferably closed at all parts to

prevent the entrance of liquid either by condensation or otherwise, the presence of which liquid would destroy the balance of the float. The hollow body or float 4 is preferably guided in its vertical movement by a pin 6, engaging in a closed bottom tube 21 arranged in the float at the top, and by means of the neck 7 arranged at the bottom of the receptacle 2, into which the needle 5 extends. Surrounding the neck 7 at the upper end is an upstanding collar 22 which prevents any sediment which may be in the liquid from clogging the outlet passage 3 or interfering with the action of the needle 5. This collar is preferably beveled or cone shaped on its inner surface to assist in guiding the needle 5 when the float 4 is initially inserted. A cock 8 is arranged below and in communication with the outlet passage 3, so that the passage may be closed when desired. The receptacle 2 is also preferably closed at the top so that its interior is not directly in communication with the atmosphere. The float is made of such size and weight that with a fixed level of fluid in the receptacle, it will rise when the gravity of the fluid reaches a certain predetermined value. The weight of the float may be adjusted by means of the loose rings or weights 12 arranged thereon. With the fluid in the receptacle standing at a certain predetermined level, an increase in specific gravity past a given degree will cause the float to rise and open the passage 3, allowing the heavy fluid to be discharged, and after the gravity decreases, the float again falls, closing the passage.

In Fig. 2, I have shown the device arranged in connection with a tank or receptacle in which gasolene is carbureted. The gasolene is maintained at a constant level in the carbureting tank 13 by the float 14 controlling the inlet 15 into the float chamber 23. The float chamber 23 communicates with the carbureting chamber through the passage 24, which extends partly above the level of the liquid to allow the pressure in the two chambers to be equalized. In this particular instance the gasolene is volatilized by blowing air therethrough, by means of the perforated pipes 16, which are preferably arranged at the level of the liquid so that some of the air is blown through the liquid and some discharged into the vapor to obtain the proper mixture. As the gasolene is volatilized, the lighter components

thereof are carried off, causing the remaining hydrocarbon to increase in gravity. The higher gravity hydrocarbons are not suitable for volatilization and unless they 5 are removed, will soon render the volatilizing device inoperative.

The receptacle 2 is connected adjacent the bottom of the well 17, by the pipe 18, so that the heavier gravity hydrocarbons may 10 flow into the gravity valve. The receptacle 2 is also connected to the receptacle 13 by the pipe 25 at a point adjacent the level of the fluid, to allow the lighter components in the receptacle 2 to pass into the carbureting 15 chamber. A connection 19 adjacent the upper part of the receptacle 2 is for the purpose of equalizing the pressure in the two chambers.

When the carbureting device is operating 20 to volatilize the lighter hydrocarbons, the heavier ones remaining in the well 17 are conducted to the receptacle 2. The presence of these heavier hydrocarbons causes the needle 5 to be unseated, thereby allowing 25 the heavier undesirable hydrocarbons to be discharged. The level of the liquid in the receptacle 2 remaining constant, it is evident that the discharge valve can be opened only by a lowering of the gravity of the 30 liquid therein. The float or tube 4 is preferably weighted or constructed so that with the liquid at a given level, its weight is counterbalanced by the displaced liquid, when that liquid is of a certain predetermined 35 gravity. Should the liquid become heavier, its buoyant effect is increased and the discharge valve is opened, allowing the heavier liquid to discharge. In the device shown in Fig. 2, the flow of the heavier hydrocarbons 40 into the receptacle 2 is substantially constant, and the needle 5 is always partly unseated allowing the heavier components to drop or trickle from the cock 8.

It is evident that the float or tube 4 need 45 not necessarily be inclosed in a separate receptacle, but may be arranged in the receptacle in which the variations of gravity occur or are produced, or in any other location where it can perform its function.

50 I claim:

1. A device of the class described comprising a receptacle having an outlet arranged adjacent the bottom, means for maintaining fluid at a constant level in said receptacle, a 55 float in said receptacle adapted to be raised by an increase of the gravity of said fluid

past a certain predetermined value, and means on said float for controlling said outlet.

2. A device of the class described comprising 60 a receptacle having an outlet adjacent the bottom, means for maintaining fluid at a constant level in said receptacle, a hollow tubular body closed at the lower end arranged in said receptacle adapted to be 65 floated by said fluid when the fluid reaches a certain predetermined gravity, means for guiding said body, and means on said body for controlling said outlet.

3. A device of the class described comprising 70 a receptacle having an outlet at the bottom thereof, an upstanding collar surrounding said outlet, means for maintaining fluid at a constant level in said receptacle, a hollow body arranged in said receptacle adapted 75 to be floated by said fluid when the fluid reaches a certain predetermined gravity, and a needle on said body for controlling said outlet.

4. The combination with a carbureting 80 chamber having an outlet of means for maintaining a hydrocarbon in said chamber at a constant level, and means operative by a variation in the gravity of said hydrocarbon for opening said outlet. 85

5. The combination with a carbureting chamber having a well at the bottom, of means for maintaining a hydrocarbon in said chamber at a constant level, a receptacle 90 having an outlet at the bottom arranged adjacent said chamber, conduits connecting said well and said chamber with said receptacle, and means in said receptacle operative by a variation in the gravity of said hydrocarbon for opening said outlet. 95

6. A device of the class described comprising 100 a vertically arranged closed cylindrical receptacle having an outlet at the bottom, a closed cylindrical float in said chamber, means for maintaining a fluid in said receptacle at a constant level, a removable weight attached to said float, means for guiding said float vertically and a needle on said float for controlling said outlet.

In testimony whereof, I have hereunto set 105 my hand at San Francisco, California, this 9th day of April, 1913.

FRED S. OLIVER.
